UNITED STATES PATENT OFFICE.

EDMOND W. T. RICHMOND, OF ROMFORD, ENGLAND.

DESIGN FOR A HOT CLOSET AND CARVING-TABLE.

SPECIFICATION forming part of Design No. 33,930, dated January 15, 1901.

Application filed December 21, 1900. Serial No. 40,691. Term of patent 7 years.

To all whom it may concern:

Be it known that I, EDMOND WALTER TYRRELL RICHMOND, a subject of the Queen of Great Britain, residing at Summercourt, Romford, Essex county, England, have invented and produced a new and original Design for a Hot Closet and Carving-Table, of which the following is a specification.

The accompanying drawing shows a front elevation of a hot closet and carving-table embodying my design.

The leading features of the design are the rectangular body portion A, having a flat top B, circular depressions C in the flat top at equal distances from its ends, and in the top at the end rectangular depressions E. Between each rectangular depression E and the adjacent circular depression there is a vertical column F, the two columns being connected 20 by a cross-bar G, at the top from which de-

pend chains H, having intermediate their length bulbous bodies I and at the bottom curved inverted covers K. The face of the body portion is ornamented by panels L of the general character or ornamental effect 25 shown and having central ornamental figures M. There is a molding N extending around the bottom of the body, and a molding O extending around the top with column-like parts P at the corners.

30 I claim—

The design for a hot closet and carving-table substantially as herein shown and described.

In testimony whereof I have hereunto subscribed my name.

EDMOND W. T. RICHMOND.
